W. H. SAUVAGE

SLACK ADJUSTER

Filed March 8, 1923

UNITED STATES PATENT OFFICE.

WILLIAM H. SAUVAGE, OF NEW YORK, N. Y., ASSIGNOR, BY MESNE ASSIGNMENTS,
TO GOULD COUPLER COMPANY, OF NEW YORK, N. Y.

SLACK ADJUSTER.

Application filed March 8, 1923. Serial No. 623,673.

To all whom it may concern:

Be it known that WILLIAM H. SAUVAGE, a citizen of the United States, residing at New York, in the county of New York and State of New York, has invented certain new and useful Improvements in Slack Adjusters, of which the following is a specification.

This invention relates to improvements in slack adjusters and more particularly to the connecting member between two relatively movable parts, the effective length of which member is adapted to be varied to take up the slack in the brake rigging, being somewhat similar to the bottom rod construction shown in my prior patents, No. 1,227,956 of May 29, 1917, for example.

One of the objects of the present invention is to provide an improved device of the above general character, and more particularly a durable and substantial bottom rod construction, which will be reliable and efficient in use and operation, and inexpensively manufactured and assembled.

A further object is to provide a device of the above general character which may be easily changed in length as the wear of the parts necessitates and which may also be readily readjusted when it is desired to restore the parts to normal position.

Other objects will be in part obvious and in part hereinafter pointed out in connection with the accompanying drawings illustrating one of various possible embodiments of the invention and in the several views of which similar reference characters denote corresponding parts. In these drawings

Figure 1 is a longitudinal sectional view of a bottom rod construction;

Figure 2 is a plan view thereof; and

Figure 3 is a cross sectional view taken approximately on the line 3—3 of Figure 1.

While the present invention will herein-after be described with relation to its application to a bottom rod construction, which is adapted to be elongated as the wear of the parts necessitate a taking up of the slack in the brake rigging, it is, of course, to be understood that this mechanism may be placed between any two relatively movable parts of the brake rigging where the effective length of the connecting part is

desired to be varied, as wear of the brake shoes or other portions of the brake rigging necessitates such variation.

Referring now to the drawing in detail, it may be assumed that 5 and 6 denote respectively the live and dead levers of the brake rigging of an ordinary car truck, and between the lower ends of these brake levers is applied the bottom rod construction which comprises a tubular member 7 pivoted at 8 to the lower end of the live lever and a rod-like member 10 pivoted at 11 to the lower end of the dead lever. The member 10 telescopes or fits within the tubular member 7 and is provided for a portion of its length with ratchet teeth 12 adapted to be engaged by a pawl 13 pivoted at 14 within a housing 15. The pawl 13 is normally urged into engagement with the teeth 12 by means of a spring 16 riveted as at 17 to the pawl. In this manner, it will be seen that as the member 10 moves relatively outwardly or towards the right with respect to the tubular member 7 the pawl 13 will engage with the teeth 12 in such a manner as to prevent a subsequent relative inward movement thereof.

After the brakes have been in use for some considerable time it is, of course, necessary to replace the worn brake shoes, at which time the parts shown in Figure 1 must be restored to their normal position. In order to easily and quickly accomplish this one or the other of the pivots 8 or 11 or swivel pin 18 is removed, thereby permitting either the part 7 or 10 to be turned relatively to the other. A quarter turn of such movement will cause the pawl or dog 13 to rise upwardly out of engagement with the teeth after which the part 10 may be telescoped within the part 7 and when the released part is again rotated back to normal position the pawl 13 will immediately fall into the proper recess. The pins 8 or 11 or 18 are then restored and the device is ready for further use.

It will thus be seen that the present invention provides a simple and practical connecting rod for interposition between two relatively movable parts of a brake rigging, the effective length of which is to be altered as desired to take up the slack in the brake rigging as wear occurs.

It will be noted particularly that the pawl 13 has a rounded rear end co-acting with the wall of the housing 15 throughout a relatively large part of its circumference, thereby forming a strong, durable and substantial abutment to take up the strains exerted upon the pawl by reason of the tremendous pressures exerted during the application of the brakes.

10 It will, of course, be understood that the invention as herein shown is directed primarily to the bottom rod construction and any of the numerous forms of temporary take-up mechanism described in my previous patents may be applied to cooperate with this bottom rod for changing the effective length either before or after the brakes are released.

I claim:

20 1. In a device of the character described, in combination, two telescoping members, one of which is provided with teeth and adapted to fit within the other, a pawl pivotally mounted in an extension upon one of said members and co-acting with said teeth said pawl having an enlarged portion co-acting with the wall of said extension, and spring means for holding said pawl in engagement with the teeth.

25 2. In a device of the character described, in combination, a tubular member having a housing formed therewith, a pawl pivotally mounted in said housing and having its rear end abutting one of the walls of said housing thereby to take up the strain exerted thereon during application of the brakes.

30 3. In a device of the character described, in combination, a tubular member having a housing formed therewith, a pawl pivotally mounted in said housing and having its rear end abutting one of the walls of said housing thereby to take up the strain exerted thereon during the application of the brakes, and a rod-like member co-acting with said tubular member provided with ratchet teeth adapted to be engaged by the pawl.

35 4. In a device of the character described, in combination, a tubular member having a housing formed therewith, a pawl pivotally mounted in said housing and having its rear end abutting one of the walls of said housing thereby to take up the strain exerted thereon during application of the brakes, and a member co-acting with said tubular member provided with ratchet teeth adapted to be engaged by the pawl, said rod-like member being concentrically disposed with respect to the tubular member, whereby a rotation thereof will throw said pawl out of engagement with the teeth and permit rela-

tive inward movement of the rod-like member.

5. In a device of the character described, in combination, a two-part telescoping push rod comprising a tubular member adapted to be connected with a brake lever, a rod-like member adapted to be pivotally connected to another brake lever, one of said members being provided with a pawl, the other of said members being provided with ratchet teeth, and a spring joined to said pawl and engaging said tubular member and adapted to hold said pawl in engagement with the ratchet teeth said pawl having an enlarged end portion co-acting with the wall of said tubular member.

6. In a device of the character described, in combination, a two-part telescoping push rod comprising a tubular member adapted to be connected with a brake lever, a rod-like member adapted to be pivotally connected to another brake lever, one of said members being provided with a pawl, the other of said members being provided with ratchet teeth, and a spring on said pawl adapted to hold said pawl in engagement with the ratchet teeth, said pawl having an enlarged portion abutting on the wall of said tubular member said tubular member and rod-like member being concentrically disposed whereby a rotation of one with respect to the other will automatically throw the pawl out of engagement with the ratchet teeth.

7. In a device of the character described, in combination, a two-part telescopic push rod comprising an inner and outer member, the outer member being provided with a housing, a pawl pivotally mounted in said housing and having its rear end on one of the walls of said housing, ratchet teeth on the inner part of said two-part push rod adapted to be engaged by the nose of the pawl, the adjacent surface of the inner and outer members being concentric whereby a relative rotation of one part with respect to the other will automatically disengage the pawl from the ratchet teeth.

8. In a device of the character described, in combination, a tubular member having a housing formed therewith, a pawl pivotally mounted in said housing and having its rear end abutting one of the walls of said housing thereby to take up the strain exerted thereon during application of the brakes, said inner member being pointed at its free end to permit ease of assembly.

In testimony whereof I affix my signature.

WILLIAM H. SAUVAGE.
